KARL T. ROMIE, OF BERKELEY, CALIFORNIA.

APPARATUS FOR FORMING CONCRETE BLOCKS.

Application filed September 4, 1925. Serial No. 54,449.

This invention relates particularly to an apparatus for and method of forming concrete blocks to be used for building purposes.

An object of the invention is to provide an apparatus for forming concrete blocks in which the concrete is poured into a suitable mold and the said mold vibrated for the purpose of controlling the density of the molded block.

10 A further object of the invention is to provide a machine for molding concrete blocks in which the concrete aggregate is poured into the mold on one level, and the said mold with the aggregate therein moved to a different 15 level and the molded aggregate ejected and the mold returned to the first level for further molding operations.

A still further object of the invention is to provide an apparatus for and method of forming concrete blocks that will be superior 20 in point of simplicity, inexpensiveness of construction, positiveness of operation, and facility and convenience in use and general efficiency.

25 In this specification and the annexed drawings, the invention is illustrated in the form considered to be the best, but it is to be understood that the invention is not limited to such form, because it may be embodied in other 30 forms, and it is also to be understood that in and by the claims following the description, it is desired to cover the invention in whatsoever form it may be embodied.

35 In the accompanying three sheets of drawings

Fig. 1 represents a side elevation of a machine for forming concrete blocks in accordance with my invention.

Fig. 2 is an end elevation of Fig. 1.

40 Fig. 3 is an enlarged fragmentary side elevation of a portion of Fig. 1.

Fig. 4 is a fragmentary side elevation partly in section of the mold shown in Fig. 3 in a discharging position.

45 Fig. 5 is a view similar to Fig. 4 showing the concrete mass discharged from the mold.

Fig. 6 is a longitudinal cross section through the concrete mold taken on the line 6—6 of Fig. 7.

50 Fig. 7 is a plan view of a portion of the mold shown in Fig. 6.

Fig. 8 is an enlarged cross section taken through Fig. 7 on the line 8—8.

Fig. 9 is an end view of the cam and guide member for controlling the direction of movement of the mold.

Fig. 10 is an enlarged section taken through Fig. 2 on the line 10—10.

Fig. 11 is a plan view taken through Fig. 3 on the line 11—11.

Figs 12 and 13 are side and end views, respectively of the vibrators mounted on the mold.

In the present day methods of forming concrete blocks, the concrete aggregate is 45 poured into suitable molds, tamped and trowelled, the mold removed, and the molded aggregate allowed to harden. The aggregate is not forced into the mold under pressure, except that incidentally obtained by the 50 tamping operation, and as a result, when the mass has hardened, it does not possess the ultimate tensile or compressive strength that it is possible to obtain in a concrete mass. Furthermore, to practice such a process 55 a large floor space is necessary, for molding the blocks and for storing the same. My invention contemplates a machine which will provide an economy in operation, upkeep and output over that of the ordinary molding 60 process, and which will also provide a finished product of a high quality, that may be sold at a lesser price than articles produced by other known processes.

In detail, the construction illustrated in the 65 drawings comprises, a frame 1 formed of vertical, longitudinal and transverse bars all joined and interconnected to form a rigid and durable structure. The frame 1 is provided with a trough or charging surface 2 on its upper side, and with a roller discharging surface 3 located on a level below that of the trough 2. The charging and discharging surfaces are shown to be substantially parallel with each other although it would be 70 clearly within the purview of the invention to vary the angularity of said surfaces. On each of the opposite sides of the frame 1, between the charging surface 2 and the discharging surface 3, I have provided a pair 75 of vertically disposed guide rods 7—7 and 8—8. The opposite ends of the guide rods

7-7 and 8-8 are securely mounted at 9 in the under surface of the trough 2 and at 10 in the upper face of the discharging surface 3. Slide members 11 and 12, respectively, are 5 mounted on the guide members 7-7 and 8-8 on the opposite sides of the machine.

A mold 13 is provided with stub shafts 14 and 15 in axial alinement, on its opposite ends, and the stub shafts 14 and 15 are 10 revolvably journaled in the respective slide members 11 and 12. The mold stub shaft 14 extends through the slide member 11 and is provided with a gear sector 15' keyed thereon. The gear sector 15' is adapted to mesh 15 with a gear rack 16 located on the frame 1 adjacent the guide members 7-7, for turning the mold throughout an arc of 180 degrees, when the said mold is moved from the charging to the discharging surface, in the manner 20 to be hereinafter described. The stub shaft 15 on the opposite end of the mold 13 is revolvably journaled in the slide member 12, and a cam member 17 is fixedly secured to said shaft, the said cam member 17 working in co- 25 operative relation to cam surfaces 18 and 19 mounted on the frame 1 adjacent the guide members 8-8. The cam 17 and the cam guides 18 and 19 are arranged on the frame 1 in a definite relationship to the gear sector 15' 30 and gear rack 16 on the opposite side of the frame, so as to regulate and control the path of movement of the mold 13 from the time that it is moved from its open face up position adjacent the charging surface 2 to the 35 open face down position adjacent the discharging surface 3.

The extreme outer ends of the mold shafts 14 and 15 have collars 20 and 21 movably mounted thereon, which said collars are 40 connected by links 22 and 23 respectively to brackets 24 and 25 mounted on the operating levers 26 and 27. The operating levers 26 and 27 are arranged on opposite sides of the frame 1, being pivoted co-axially to the opposite 45 sides of the frame at 28. The lower ends of the arms 26 and 27 are provided with counter-balance weights 29 and 30 thereon.

The mold 13 is substantially rectangular in its outward contour and consists of a continuous 50 perimetral wall 31, a substantially closed bottom 32, transverse division members 33 and mold cores 34 suitably disposed within the space between the division members. The mold cores 34 are secured at their lower ends 55 to the bottom 32 of the mold. The form of the mold shown in Figs. 6, 7 and 8 is calculated to cast four blocks substantially 8-shaped, although it would be clearly within the purview of the invention to form a mold 60 with a greater or a lesser number of compartments therein to form blocks or products of a different character and shape. Within each one of the compartments of the mold 13, I have provided an ejector frame member 35 65 which is approximately of the same size as the

interior of the mold, the frame 35 being adapted to move freely within the mold and in and around the cores 34 therein. The frame 35 on its inside and outside edges adjacent the walls of the mold, and the face walls of the cores 34, is provided with resilient and yielding strips 36 thereon. The strips 36 bound the inner and outer perimeters of the frame 35 and have a scraping contact with all of the vertical surfaces in the 70 mold. The strips 36 are intended to exert a wiping action on the faces of the mold and cores, with which they come in contact, so as to cleanse the mold faces of any concrete mix adhering thereto, after each and every molding operation. I have found that in order to eject the concrete aggregate from the mold after the aggregate has been thoroughly vibrated therein, it is good practice to cover the upper face of the ejector frame 35 with a 75 screen or other equivalent foraminated surface 37. In order to hold the screen over the face of the ejector 35, I wrap the said screening around a removable plate 38 which in turn is secured to the frame 35 by means of 80 bolts or screws 39. The concrete aggregate that is molded on the screen surfacing of the ejector frame 35 can be discharged from the mold without any portion of the aggregate 85 adhering or sticking to the ejector. In my 90 experiments I have found that no other material will separate itself from the concrete aggregate as efficiently as the screening material, due almost entirely to the fact that the screen permits of an air circulation and prevents any suction or vacuum effects between 95 the face of the concrete block and the screening.

The ejector frame 35 in each one of the mold compartments is provided with a downwardly extended shaft 40, each one of which is securely bolted into the transverse bar 41 adapted to connect all of the ejector shafts 40 together. The opposite ends of the bar 41 are provided with pins 42 and 43 thereon, in axial alinement, for the purpose to be hereinafter described. On opposite sides of the mold 13 I have secured vibrators 43 and 44, each of which consists of an electrically driven motor 45 having a notched wheel 46 on the armature shaft which is adapted to intermittently strike a lever 47 pivoted to the motor frame at 48. The lever 47 is provided with one end thereof in contact with the surface of the mold so as to strike said mold and as the lever is actuated at a high rate of speed to vibrate the mold and its contents.

In the operation of the molding apparatus, the plastic concrete aggregate would be piled into the trough 2 on the charging surface of 125 the frame 1. The open upper surface of the mold 13 registers with an opening 49 cut through the surface of the trough 2. With the open upper face of the mold registering 130 with the opening 49 through the trough 2,

the ejector frames 35 in the mold would be positioned adjacent the bottom of said mold. The operator would then fill the mold from the trough and when the mold is properly 5 filled, would set the vibrators 47 in motion so as to vibrate or agitate the plastic concrete aggregate in the mold. The vibration causes the aggregate to thoroughly pack itself within the mold and to eliminate all air spaces 10 from the interstices of the aggregate and to work the aggregate into a solid and dense mass. Vibration of the aggregate in this manner will cause the mass when hardened to have very high tensile and compressive 15 strength, far above that possessed by concrete blocks that are formed under pressure. After the mass in the mold has been thoroughly vibrated, the upper surface thereof would be trowelled off smoothly. 20 The operator would then grasp the handles 26 and 27 to lower the mold 13 and slide members 11 and 12 on the respective guide members 7-7 and 8-8. As the mold 13 approaches the gear rack 16 the gear 15' 25 engages therewith and the cam member 17 disengages from the cam surface 18, permitting the gear sector 15' to turn the mold 13 through an arc of 180 degrees to place the said mold open face downward. Continuing 30 the downward movement of the mold, causes the open face thereof to be brought into registry with a pallet 51 positioned on the discharging surface 3, as shown in Fig. 4. In this position, the pins 42 and 43 on the bar 35 41 pass under and contact with the under edges of the trip arms 52 pivoted on opposite sides of the frame. The trip arms 52 are pivoted on the pins 53 secured on opposite sides of the frame 1 and said trip arms are provided 40 with a forwardly extended handle member 54 which projects over the front end of the frame 1. With the upper surface of the mold 13 resting on the pallet 51, the operator moves the handles 26 and 27 upwardly, 45 which action causes the mold to be raised, but the edges of trip members 52 hold the ejector frames 35 in a relatively immovable position, and causes the contents of the mold to be ejected therefrom, in the manner illustrated in Fig. 5. The operator is enabled 50 to raise the mold 13 until the bottom thereof contacts with the ejector frame bar 41, thus virtually positioning the screen surface of the ejectors on a plane flush with the open face 55 of the mold 13. When the concrete block has been ejected from the mold, the operator releases the trip members 52 from contact with the pins 42 and 43 on the ejector bar 41, and permits the mold to be swung through- 60 out an arc of 180 degrees into the open face up position, at which time the edges of the trip bar 52 would reengage the pins 42 and 43 on the bar 41 so that during the last portion 65 of the upward stroke of the handles 26 and 27 the ejector frames 35 in the mold are moved from a position adjacent the open upper face thereof to the bottom thereof. In this position, the apparatus is again in readiness for the molding operation. Repeated usage of my apparatus has established that 70 concrete blocks may be formed more efficiently and with a much lesser outlay for apparatus and floor space than that necessary where other processes of forming concrete blocks are used. The concrete blocks that 75 are formed in my machine are of such hardness that the same can be stacked within a few hours time after they have been molded, whereas, it is not possible to do this with concrete blocks formed by other processes, 80 where it is necessary to allow the concrete blocks to harden for a day or so before stacking the same. In order to place the pallet 51 in proper registry, to have the concrete blocks discharged thereon, I have provided a pair 85 of gravity stops 60 on the discharging surface 3 by which the said pallets may pass when loaded with the concrete blocks. 90 Having thus described this invention, what I now claim and desire to secure by Letters Patent is:

1. A device of the character described comprising a mold movably mounted on a frame, an ejector movably mounted in said mold, resilient yielding strips mounted on the ejector such strips being adapted to have a scraping contact with the vertical sides of the mold, means to invert said mold with said ejector; means to elevate said mold when inverted; and means to hold said ejector stationary while said mold is being elevated. 95
2. A device of the character described comprising a frame, a mold having an open side movably mounted on said frame; an ejector in the bottom of said mold, said ejector having resilient strips mounted thereon adapted to have a scraping contact with the vertical sides of the mold, the upper face of said ejector being covered with a screen, means to invert said mold with said ejector; and means to hold 105 said ejector stationary while said mold is elevated. 110
3. The combination with a mold having an ejector therefor and a plurality of resilient strips secured to said ejector, said strips being adapted to contact with the vertical sides of said mold and exert a scraping action on the same. 115
4. The combination with a mold having an ejector therefor and a plurality of resilient strips secured to said ejector, said strips being adapted to contact with the sides of said mold to exert a scraping action on the same, a movable plate for said ejector, said plate having a covering of screen material wrapped thereon. 125
5. A device of the character described comprising a frame; a mold having an open side movably mounted on the frame; an ejector 130

in the bottom of said mold; means to invert said mold and ejector, said ejector having resilient strips thereon adapted to exert a scraping and wiping action on the vertical faces of the mold with which they come in contact, a removable plate secured to said ejector, said removable plate having a screen

thereon; means to elevate said mold; and means to hold said ejector stationary while said mold is elevated.

10 In testimony whereof, I have hereunto set my hand at San Francisco, California, this 6th day of July 1925.

KARL T. ROMIE.
